UNITED STATES PATENT OFFICE.

LEWIS FRITZ, OF CHICAGO, ILLINOIS.

CRADLE.

Application filed July 28, 1922. Serial No. 578,054.

To all whom it may concern:

Be it known that I, LEWIS FRITZ, a citizen of the United States, and a resident of the city of Chicago, county of Cook, and State of Illinois, have invented certain new and useful Improvements in Cradles, of which the following is a specification.

My invention relates to new and useful improvements in Cradles, and has for its principal object the provision of an improved construction of this character, which will be highly efficient in use and economical in manufacture.

Among the salient objects of the invention is to provide a motion which will be automatically imparted through the medium of an electric motor or spring motor and which can be adjusted to regulate the speed of the rocking motion of the same.

Other objects will appear hereinafter.

The invention consists in the combinations and arrangements of parts hereinafter described and claimed.

The invention will be best understood by reference to the accompanying drawings, forming a part of this specification, and in which,

Fig. 1, is a side elevational view of a cradle, embodying the invention, and

Fig. 2, is a sectional detail view of the same taken substantially on line 2—2 of Fig. 1.

In carrying the objects of the invention into effect, I provide oppositely disposed hollow standards 5 and 6 mounted in spaced relation with respect to each other and held in such relation by tie members 7, as illustrated, one of said standards being provided with an enlarged housing 8 at its lower extremity, the purpose of which will be more fully hereinafter understood. At the outer extremities of the standards 5 and 6 are lateral projecting supporting studs 9 carrying link members 10 through the medium of ball and socket joints 11. The link members 10 carry the crib or basket 12 and are secured to lateral projections 13 carried by the crib or basket 12, as illustrated.

The means for imparting rocking motion to the crib 12 comprises a rocker arm 14 having one end fixed to a lateral projecting stud 15 through the medium of a bolt 16 and having its other end connected to a gear 17 through the medium of a bolt 18. The gear 17 is confined in the housing 8 and

meshes with a gear 19 of considerably smaller diameter carried on the shaft 20 of a motor 21 also confined in the housing 8. In this instance the motor 21 represents an electric driven motor, however, the driving means can be a spring-driven motor or the like according to the desire. I prefer to make the wall portion 22 of the housing 8 removable to gain access to the interior of the housing 8, said wall portion 22 being secured in place by any suitable means. When the motor is in operation a rocking motion is imparted to the crib through the rocker arm 14, which is driven by the gears 17 and 19.

In order to regulate the rocking motion of the crib 12, I provide a number of holes 23 in the gear 17 into which the bolt 18 is adapted to be screw-threaded, each of said openings 23 being a greater distance from the center of the gear than the other and as such when the rocker arm 14 is mounted in the position of the openings 23 a greater or less rocking motion will be imparted to the crib 12, as will be readily understood.

I also provide a canopy 24 over the crib 12 which comprises a suitable frame 25 carrying mosquito netting 26, or the like, as a roof having portions of mosquito netting depending from the outer side edges of the frame as indicated at 25', said frame 25 comprises parts hingedly connected together by means of a transverse pintle 27' carried by adjustable supports 27, said parts being held in the position illustrated in Fig. 2 by suitable arms 26', carried by the supports 27. The adjustable supports 27 are mounted in the upper portions of the hollow standards 5 and 6, as illustrated in Fig. 1, and are held in the desired adjustable position through the medium of thumb bolts 28.

Referring to Fig. 1 of the drawing, it will be noted that I associate with the crib 12 a pendulum 12', the purpose of which is such that when desired the link member 14 can be detached from connection with the member 15 and oscillatory movement can be manually imparted to the crib, the pendulum serving to keep the crib in oscillatory movement a greater length of time.

It is primarily my object to provide an automatically rocked baby crib whereby the attendant need pay but little attention to the occupant of the crib and thereby be able to attend to other domestic duties or the like. The construction of the crib is of a simple

2
nature and the cost of manufacture will be repaid by the convenience afforded during the use of the crib.

While I have illustrated and described the 5 preferred form of construction for carrying my invention into effect, this is capable of variation and modification without departing from the spirit of the invention. I, therefore, do not wish to be limited to the precise 10 details of construction set forth, but desire to avail myself of such variations and modifications as come within the scope of the appended claim.

Having described my invention, what I 15 claim as new and desire to secure by Letters Patent is:

A cradle comprising supports in spaced relation with respect to each other; lateral studs at the upper extremities of said supports; a crib; means for supporting said crib 20 by said supports for oscillatory movement,

said means comprising lateral projections on said crib, link members fixed to said projections, and connections between said link members and said lateral studs; a lateral 25 projection at one end of said crib; a housing at the lower extremity of one of said supports having a removable wall portion; and means arranged in said housing for oscillating said crib, said means comprising a motor, 30 a gear on the shaft of said motor, and a gear meshing with said first named gear; and an arm having one end fixed to said lateral projections at the end of said crib and the other end adjustably connected to said second 35 named gear.

In testimony whereof I have signed my name to this specification in the presence of a subscribing witness.

LEWIS FRITZ.
